UNITED STATES PATENT OFFICE.

CHARLES A. MINER, OF KALAMAZOO, MICHIGAN, ASSIGNOR TO LIMOUSINE TOP COMPANY, OF KALAMAZOO, MICHIGAN.

DOOR AND WINDOW FOR VEHICLE-BODIES.

1,298,763.

Specification of Letters Patent.

Patented Apr. 1, 1919.

Application filed February 20, 1917. Serial No. 149,740.

To all whom it may concern:

Be it known that I, CHARLES A. MINER, a citizen of the United States, residing at the city and county of Kalamazoo, State of Michigan, have invented certain new and useful Improvements in Doors and Windows for Vehicle-Bodies, of which the following is a specification.

My improvements are particularly designed by me for embodiment in doors of automobile bodies of the convertible type which comprise a lower body portion and an upper body portion removably mounted thereon, the upper body portion being separable along a horizontal line. In such structures it is necessary to provide an upper door section adapted to be connected to the lower section when the demountable body portion is in position. My improvements, however, are not limited to vehicle bodies of the convertible type but may be utilized to advantage in connection with other types.

The main object of the invention is to provide a door or window structure for vehicle bodies in which the panes may be adjusted to open or close the same. A further object is to provide a structure of this character in which the parts are supported so that vibration and rattling is prevented and so that the adjustments may be very easily accomplished.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing, forming a part of this specification, in which:

Figure I is a detail inside elevation of a vehicle body embodying the features of my invention, the walls of the upper and lower sections being shown conventionally.

Fig. II is an enlarged detail vertical section on a line corresponding to line 2—2 of Fig. I.

Fig. III is a similar detail section showing the upper pane partially lowered.

Fig. IV is an enlarged detail horizontal section taken on a line corresponding to line 4—4 of Fig. I.

Fig. V is an enlarged detail horizontal section taken on a line corresponding to line 5—5 of Fig. I.

Fig. VI is a perspective view of one of the supporting slides for the upper pane. 60

Fig. VII is a detail vertical section on a line corresponding to line 7—7 of Fig. IV, showing structural details.

In the drawing similar reference characters refer to similar parts throughout the several views, and the sectional views are taken looking in the direction of the little arrows at the ends of the section lines.

Referring to the drawing, the reference character 1 indicates the lower permanent portion of an automobile body and 2 the upper demountable portion thereof, the two portions being separable upon a line 3. The door, in the embodiment illustrated, comprises a lower portion 4 hinged to the lower part of the body by means of the hinges 5 and provided with a handle or latch 6 and an upper portion 7 hinged to the upper or demountable part of the body by means of the hinges 8, but the upper and lower parts 80 of the door are also separable on the line 3.

The upper portion of the door comprises a frame and upper and lower panes 9 and 10, respectively. The frame is provided with facing grooves or channels 11 adapted to 85 receive the ends of the panes 9 and 10, the grooves being formed by an integral outer stop 14 and removable inner stop 15. The stop 15 is shouldered at its lower end to receive the lower pane 10 which is supported 90 by the parting strip 13 arranged in a groove 12 in the frame. This parting strip is of thin metal in order to permit a close fitting of the parts. The lower pane 10 is provided with a packing 16 at its ends which prevents 95 its rattling and also to a degree relieves it from shocks. The upper pane 9 is provided with channel-shaped slides 17 fitted over its ends, the slides being preferably provided with facings 18 folded so as to provide inner and outer facings, as shown in Figs. IV and V, the facings being a piece of fabric suitably glued to the channel and embracing the edge of the upper pane so that it is securely held within the channel against vibration and rattling. The facing for the channel or slide prevents it rattling in the groove. The upper pane is arranged so as to overlap and slide past the outer side of the lower pane. 100

111

The upper portions of the stops 15 are rabbeted at 24, the rabbeted portions being notched at 23 to provide keepers coacting with the spring stops 25 which are mounted on the slides and engaged behind the stops under spring tension to coact with these keepers. These spring stops are provided with finger pieces 26 which project to the inside so that the occupant of the vehicle 10 may conveniently manipulate the same, the finger pieces being disposed so that they form handles for lifting or for pushing the pane downwardly, as may be desired. By this simple arrangement of parts the upper pane is supported so that it may be adjusted as occasion requires and also the parts are simple and economical to produce and may be easily assembled so that they do not rattle.

15 I have illustrated and described my improvements in the form in which I have embodied the same for the market. I have not attempted to illustrate or describe certain modifications in structural details which I contemplate as I believe the disclosure made will enable those skilled in the art to which my invention relates to embody or adapt the same as may be desired.

20 Having thus described my invention, what I claim as new and desire to secure by Letters Patent, is:

25 1. In a structure of the class described, the combination of a frame provided with opposed grooves adapted to receive panes, upper and lower panes, the upper pane being adjustable and arranged to overlap and slide past the outer side of the lower pane, inner stops shouldered to receive the lower pane,

the portion of said stops above the lower pane being rabbeted on their inner sides and 40 notched to provide keepers, thin metal parting strips disposed on the outer side of said lower pane to support the same, and channeled metal slides arranged on the ends of the upper pane and disposed in said grooves, 45 said slides being provided with inner and outer fabric facings and with spring catches engaged under spring tension with the rabbeted portions of said stops and adapted to coact with said keepers to adjustably support the upper pane.

2. In a structure of the class described, the combination of a frame provided with opposed grooves adapted to receive panes, upper and lower panes, the upper pane being 50 adjustable and arranged to overlap and slide past the outer side of the lower pane, inner stops shouldered to receive the lower pane, the portion of said stops above the lower pane being rabbeted on their inner sides and 55 notched to provide keepers, and channeled metal slides arranged on the ends of the upper pane and disposed in said grooves, said slides being provided with inner and outer fabric facings and with spring catches 60 engaged under spring tension with the rabbeted portions of said stops and adapted to coact with said keepers to adjustably support the upper pane.

65 In witness whereof, I have hereunto set 70 my hand and seal in the presence of two witnesses.

CHARLES A. MINER. [L. S.]
